(57) **CLAIM**

The ornamental design for a printer, as shown and described.

DESCRIPTION

FIG. 1 is a perspective view of the top, front, and right side of a printer showing our new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof;

FIG. 7 is a bottom plan view thereof; and,

FIG. 8 is another perspective view similar to FIG. 1 showing the exhaust tray in opened position.

The broken lines are for purposes of illustration only and form no part of the claimed design.

1 Claim, 7 Drawing Sheets
